UNITED STATES PATENT OFFICE

CHARLES H. AYARS, OF SALEM, NEW JERSEY, ASSIGNOR TO AYARS MACHINE COMPANY, OF SALEM, NEW JERSEY, A CORPORATION OF NEW JERSEY.

LIQUID SUPPLY MECHANISM

Application filed January 8, 1930. Serial No. 419,427.

This invention relates to can filling machinery and has particular reference to mechanisms for introducing a predetermined quantity of liquid into cans in continuous sequence.

In my co-pending application, Serial No. 385,243, filed August 12, 1929, I illustrated and described an apparatus for positioning cans so that the upper outward annular flanges of the same overlap and as the cans were passed under a hopper, a continuous stream of liquid was passed therefrom and into said cans, spilling being prevented by the overlapping flanges.

The type of machine to which this invention has been applied is illustrated and described in my Patent Nos. 1,828,167, granted October 20, 1931, and 1,818,780, granted August 11, 1931, although the invention may be applied to other machinery with equally good results.

The object of this invention is to provide mechanism whereby a predetermined quantity of liquid may be served into each can when, and only when, the machine to which the same is applied is operating.

A further object, conversely stated, is to provide a mechanism which insures the serving of liquid to the cans when the machine is being operated.

According to the invention the liquid supply mechanism for introducing a predetermined quantity of liquid into successive cans is provided with a regulating valve and with a valve which controls the flow of liquid, and the latter valve is coupled with the operating lever of a can filling machine so that liquid is admitted to said cans during the operation of the can filling machine, and the supply is entirely cut off when the can filling machine is at rest.

The drawing illustrates an embodiment of the invention and the views therein are as follows:

Figure 1 is a perspective view of a machine such as disclosed in the patents above mentioned, and is shown herein in dotted lines with the apparatus of the invention shown in full lines in its association therewith,

Figure 2 is a front view of the regulating and dispensing means for the liquid, and

Figure 3 is a vertical section through the valves.

The machine illustrated in dotted lines in Figure 1 is a can filling machine of the rotary type and is driven from a belt from any source of power passing over the pulley 6 mounted on a shaft which includes a clutch 7. The machine is thrown into or out of engagement with the source of power by means of the shipper handle 8.

The feed of the cans 9 under the upwardly curved plate 11 through the medium of the can feeding and positioning mechanism 12 is explained in my co-pending application, Serial No. 385,243, filed August 12, 1928, and above referred to.

A fluid supply pipe 13, shown in Figure 1, extends from a source (not shown) and at a suitable point above the liquid directing box 14 is provided with a regulating valve 16 for increasing or decreasing the orifice through which the liquid is permitted to pass from the pipe 13.

The size of orifice is controlled by the hand lever 17, while the indicating plate 18, combined with the pointer 19, is fixedly mounted so as to rotate with the hand lever 17 and form visible means for apprising the operator of the size of orifice provided in the valve.

Below the regulating valve 16, and still above the top of the liquid directing box 14, is a gate valve 21 which is opened or closed through the link 22 controlled by the connecting rod 23 and whose one end is connected to said link, while its other end is connected to the shipper handle 8 at the point 24 in Figure 1.

The valve 21 is of such type that it may readily permit the passage therethrough of the greatest volume of liquid which may, at any time, pass through the regulating valve 16 so that, regardless of the position of the lever 17 so as to change the orifice or passageway in the valve 16, the gate valve 21 will permit the complete passage of the liquid from said regulating valve into the liquid directing box 14 when said gate valve 21 is opened.

On the other hand, regardless of the position of the lever 17, no liquid may ever pass down through the gate valve 21 into the liquid directing box 14 when the valve 21 is closed.

5 Nor is it ever desired that liquid should pass down into the cans 9, except when the entire can filling machine, which I shall designate A, is in operation. It, therefore, 10 follows that when the shipper handle 8 is in the position shown in Figure 1, the gate valve 21 is entirely closed and no liquid flows through pipe 13 into the liquid directing box 14, although the regulating valve 16 is open for the passage of a predetermined 15 quantity of liquid, whenever an outlet is provided through the gate valve 21.

In order to start the machine it is necessary to throw the shipper handle 8 in the 20 direction indicated by the arrow, and in so doing, the can filling machinery is set in operation and the gate in the valve 21 is opened so that the entire contents which pass through the regulating valve 16 will pass 25 down through the pipe 13 into the liquid directing box 14 where it is directed into the cans 9, as explained in my co-pending application above mentioned.

When the machine, for any reason, is 30 stopped by moving the shipper handle 8 in a direction contrary to the direction of the arrow, the gate in the valve 21 is simultaneously closed and admission of the liquid 35 through the pipe 13 to the liquid directing box 14 is immediately discontinued.

Of course, the liquid supply mechanism 40 for can feeding machinery illustrated may be modified in various ways without departing from the invention herein set forth and hereafter claimed.

The invention is hereby claimed as follows:

In combination with a can filling machine 45 having an operating handle, of means comprising a fluid pipe for supplying liquid to said cans and having a gate valve in said pipe for opening and closing the passage-way for said liquid, and means connecting said gate valve with the operating handle 50 of said machine whereby the gate valve is fully opened when the machine is operated and totally closed when the machine is stopped.

55 In testimony whereof I have signed my name to this specification.

CHARLES H. AYARS.
